UNITED STATES PATENT OFFICE.

ROBERT E. McCUALEY, OF STOCKTON, CALIFORNIA, ASSIGNOR TO J. M. CONLEY COMPANY, INC., OF STOCKTON, CALIFORNIA.

SCRAPER.

1,402,078.

Specification of Letters Patent.

Patented Jan. 3, 1922.

Application filed December 13, 1919, Serial No. 344,575. Renewed June 2, 1921. Serial No. 474,527.

To all whom it may concern:

Be it known that I, ROBERT E. McCUALEY, a citizen of the United States, residing at Stockton, in the county of San Joaquin, 5 State of California, have invented certain new and useful Improvements in Scrapers; and I do declare the following to be a full, clear, and exact description of the same, reference being had to the accompanying 10 drawings, and to the characters of reference marked thereon, which form a part of this application.

This invention relates to improvements in scrapers or levelers of the kind used to 15 grade and level dirt, and preferably drawn by a tractor connected thereto by a rigid drawbar.

The principal object of the invention is to 20 devise a scraper which besides scraping the dirt, embodies features enabling it to transport a load of dirt to any desired point for dumping without scraping the ground over which it is being transported.

In all scrapers constructed to-day, as far 25 as I am aware, no provision is made for carrying dirt any distance, and if the dumping ground is far from the area being scraped or leveled, by the time the scraper has reached the dump, the majority of the 30 dirt presumed to be carried thereby has been lost by reason of the fact that the scraper has no bottom, and hence with the jarring or bumping motion along the ground, the back or scraping plate of the 35 scraper leaves the ground and allows the dirt to escape thereunder.

In my improved scraper, I have eliminated the defect cited above, by combining in one, the features of a scraper plate and 40 a carrying bowl, and providing means for instantly changing the functioning of this member from a scraper to a carrying bowl or vice versa.

A further object of the invention is to 45 so arrange the control means that it may readily be operated by the driver of the tractor from his seat thereon, without physical exertion on his part, by manipulation of the tractor itself, as will be seen here- 50 inafter.

A further object of the invention is to produce a simple and inexpensive device and yet one which will be exceedingly effective for the purposes for which it is designed.

55 These objects I accomplish by means of

such structure and relative arrangement of parts as will fully appear by a perusal of the following specification and claims.

In the drawings similar characters of reference indicate corresponding parts in 60 the several views.

Fig. 1 is a top plan view of the scraper.

Fig. 2 is a side elevation thereof showing the same in scraping position.

Fig. 3 is a sectional elevation showing the 65 scraping member in position to transport a load.

Referring now more particularly to the characters of reference on the drawings, the numeral 1 denotes a pair of vertical and 70 suitably spaced plates, forming the sides of the scraper, to which are secured ground bearing runners or shoes 2.

At the upper and lower corners of the 75 rear end of the plates are bolts 3 on which are spacer pipes or sleeves 4.

At the forward end, substantially half-way up, is a transverse beam 5 extending between the plates 1 and rigidly secured thereto.

Substantially central of the plates is a shaft 6 covered by a strong sleeve 7, on which are turnably mounted a pair of spaced bosses 8 to which are secured beams 9 projecting forward of the plates 1 and 85 being secured to the beam 5. These beams converge somewhat at their forward ends, and have cross bars 10 secured thereto, which take the strain of and are connected to the drawbar 11 of the tractor pulling the 90 device.

Secured on the sleeve 7 are a plurality of bosses 12 from which extend rearwardly spiders or webs 13, whose outer edges are concentric with the shaft 6.

To such outer edges is secured a plate 14 extending between the plates 1, this plate being substantially semicircular and forming at once a scraper plate and a carrying bowl.

The radius of curvature of this plate is greater than the distance from the shaft 6 to the ground for a purpose which will appear.

Fixed to the sleeve 7 is a lever 15 having 105 a spring pressed catch or pawl 16 thereon, of the usual construction, which engages with a ratchet quadrant 17 secured both to the beam 5 and to the sleeve 4, the teeth 17^a of which quadrant point toward the rear.

A light cable or rope 18 is attached to the actuating handle 16^a of the pawl, which cable projects forward to within reach of the driver of the tractor.

5 In operation, the scraper plate 14 is positioned as shown in Fig. 2, so that the lower or scraping edge thereof is somewhat below the level of the shoes 2. This distance may be regulated by movement of the lever 15 prior to commencing the job. When a sufficient quantity of dirt has been scraped to constitute a load, the tractor is backed up somewhat, pushing back on its rigid drawbar. This causes the body or frame of the 10 scraper to back up, while the scraper member 14, being in contact with the ground remains relatively stationary, and being fixed on the turnable sleeve 7, assumes a horizontal position as shown in Fig. 3, the lever 15 of course likewise moving and taking up a new position on the quadrant 17. Then when the tractor is moved forward, the member 14, now a bowl, drags on the ground, and transports a full load of dirt to whatever point desired, the setting of the quadrant teeth 17^a preventing the pawl 16 from movement out of the tooth in which it is held, and so preventing movement of the lever and consequently of the bowl.

15 30 When the scraper has arrived at the place where it is desired to dump the load, the driver of the tractor, while still keeping the latter in forward motion, pulls the cable 18, thus freeing the lever 15 and bowl 14 connected thereto, and allowing the latter to rock and upset and so dump its load. With this movement, the lever 15 will descend and bump against the beam 5, in which position the lower edge of the scraper plate 14 is 35 above the level of the shoes 2, permitting the latter to ride on the ground and allowing the dirt to escape under the plate 14.

In this latter and adjacent positions, the device may be used to level or scrape off 40 high spots, the shoes or runners of the side plates bearing on the ground.

45 From the foregoing description it will be readily seen that I have produced such a device as substantially fulfills the object of 50 the invention as set forth herein.

While this specification sets forth in detail the present and preferred construction of the device, still in practice such deviations from such detail may be resorted to 55 as do not form a departure from the spirit of the invention, as defined by the appended claims.

Having thus described my invention, what I claim as new and useful and desire to secure by Letters Patent is:—

60 1. A scraper including a frame adapted to be attached to the rigid drawbar of a tractor, a concave scraper plate turnably mounted in the frame, and means whereby 65 the scraper plate will be automatically

70 moved from a substantially vertical scraping position to a horizontal carrying position with a backward movement of the tractor.

75 2. A scraper including a frame adapted to be attached to the rigid drawbar of a tractor, a concave scraper plate turnably mounted in the frame, means for automatically altering the setting of the plate relative to the frame with a backward movement of the tractor, and means for holding the plate in any desired setting when the tractor moves forward.

80 3. A scraper comprising a frame adapted to be secured to the rigid drawbar of a tractor, a concave scraping member turnably mounted in the frame and adapted to rest on the ground, and means actuated by the backward movement of the tractor for positioning the scraping member in a dirt carrying position.

85 4. A scraper comprising a frame adapted to be secured to the rigid drawbar of a tractor, a concave scraping member turnably mounted in the frame and adapted to rest on the ground, a lever secured to the scraping member, means whereby the setting of the scraping member may be moved to a carrying position with a backward movement of the tractor, and means co-acting with said lever actuated by the driver of the tractor for again reversing the setting of the scraping member with the forward movement of the tractor.

90 5. A scraper comprising a rigid frame adapted to be attached to the rigid drawbar of a tractor, a transverse shaft therein, a scraping member turnable on the shaft and constantly bearing on the ground whereby a backward movement of the tractor will automatically move the scraping member about the shaft, a lever attached to the scraping member, a pawl on the lever, and a ratchet quadrant fixed to the frame and with which the pawl engages; the ratchets of said quadrant pointing to the rear, whereby the scraping member may have free rotation with the backward movement of the tractor the lever moving therewith, but will be held against rotation in the opposite direction unless the pawl is retracted from the ratchets.

95 6. A scraper including a frame adapted to be attached to the rigid drawbar of a tractor, a concave scraper plate turnably mounted in the frame, means for automatically altering the setting of the plate relative to the frame with a backward movement of the tractor, and a common control means whereby the plate may be dumped or reset for scraping either manually or with the forward movement of the tractor.

100 In testimony whereof I affix my signature.

ROBERT E. McCUALEY.
